UNITED STATES PATENT OFFICE.

ARTHUR M. HARRINGTON AND ROBERT F. SCOTT, OF PHILADELPHIA, PENNSYLVANIA, ASSIGNORS TO EDWIN HARRINGTON, SON & CO., INC., OF PHILADELPHIA, PENNSYLVANIA, A CORPORATION OF PENNSYLVANIA.

BOLT-FACING MACHINE.

1,090,298.

Specification of Letters Patent.

Patented Mar. 17, 1914.

Application filed July 3, 1913. Serial No. 777,355.

To all whom it may concern:

Be it known that we, ARTHUR M. HARRINGTON and ROBERT F. SCOTT, citizens of the United States, and residents of the city 5 of Philadelphia, county of Philadelphia, and State of Pennsylvania, have invented certain Improvements in Bolt-Facing Machines, of which the following is a specification.

10 This invention relates to means for facing bolt heads, and its leading object is to turn a face of any desired character.

It is frequently required that stay bolt heads have an under cut facing, for instance 15 where it is required that copper gaskets be held between the bolt heads and the boiler sheet, and our improvements are well adapted for turning such facings.

The preferred construction comprises the 20 combination with means for revolving a bolt, of guiding means, a slide reciprocating therein, a tool holder journaled on the slide, a cam adapted to rock the tool holder and a device engaging the cam to adjust the position 25 of the tool in the facing operation.

The characteristic features of our improvements are fully disclosed in the following description and the accompanying drawings in illustration thereof.

30 In the drawings, Figure 1 is a broken vertical sectional view of a stay bolt machine having our improvements applied thereto; Fig. 2 is a broken sectional plan view of the same; and Fig. 3 is a broken sectional view 35 taken on the line 3—3 of Fig. 2.

The machine, as illustrated in the drawings, comprises a frame 1, a stock 2 revolute on the bearing 1' and fixed to a shaft 3 which is journaled in the frame, a beveled 40 spur gear 4 which is fixed on the shaft, a beveled pinion 5 which engages the wheel 4 and a shaft 6 which is journaled in the frame and has the wheel 5 fixed thereon, the stock revolving a bolt 7 set therein. A 45 guide 8 is fixed to the bearing 1' of the frame, radially to the stock 2, and contains the way 8'. A slide 9 is movable in the way 8', having the part 9' movable in the way 8'. The slide is provided with the bearings 10 in which are mounted the journals 11 and 11' of the tool holder 12, the latter being provided with a tool 13 for facing the head 7' of the bolt. A bolt 14 passes through the tool holder 12 and engages the slide 9, and a

spring 12' is disposed, in the socket 12'', between the holder 12 and the bolt head 14', the spring acting to depress the tail of the tool holder. A rearwardly extending cam arm 15 is fixed to the journal 11 and a bearing 16 for a roller 16' is screwed in the slide, 60 the roller engaging the cam arm. The slide 9 is connected by a link 17 with a crank lever 18 which is fulcrumed on the frame, and a crank lever 19, fulcrumed on the frame, is connected with the lever 18 by a link 20. A 65 weight 21 on the arm 19' of the lever 19 acts through the parts 17, 18 and 20 to retract the slide 9 with the parts thereon.

When it is desired to face the bolt head 7', the operator presses down the treadle 19'', 70 rocks the lever 19, and moves the slide 9 along the guide 8 so that the tool 13 turns a face on the head 7' of the revolving bolt 7. The cam arm 15 is held in contact with the roller 16', by gravity and the action of the spring 75 12', and acts through the journal 11 and tool holder 12 to adjust the position of the tool 13 in the cutting operation, the cam shown being adapted for producing an under cut face. Any desired face can be cut by the use 80 of an appropriate cam.

In producing plane facings, the bearing 16 is detached so that the cam 15 is rendered inoperative and the tool holder is fixed to the slide 9 so that in moving the slide the tool 13 85 cuts a flat face on the head of the bolt revolved in contact therewith.

Having described our invention, we claim:

1. In a bolt machine, the combination with a revoluble stock, a guide, a slide controlled 90 by said guide, a holder provided with a tool journaled in said slide, and means for tilting said tool holder and tool as said slide moves along said guide.

2. In a bolt machine, the combination with 95 a revoluble stock, a guide, a reciprocating slide controlled by said guide, a journaled tool holder mounted on said slide, a cam arm fixed to said tool holder and means engaged by said cam arm for tilting said tool holder 100 as said slide moves along said guide toward said stock.

3. In a bolt machine, the combination with 105 means for engaging and revolving a bolt having a head, of means comprising a reciprocating journaled holder having a tool adapted for facing said head, and means whereby said holder is moved and said tool

is caused to turn an under-cut facing on said head.

4. In a bolt machine, the combination with means for holding and revolving a bolt having a head, of a guide, a reciprocating slide controlled by said guide, mechanism comprising a treadle for moving said slide along said guide, a holder provided with a tool journaled in said slide, a cam arm fixed to said holder and means fixed to said guide for engaging said cam arm and adjusting said tool in facing the head of said bolt.

5. In a bolt machine, the combination with means for revolving a bolt, of a guide, a slide adapted to reciprocate along said guide, a journaled tool holder carried by said slide and means for reciprocating said slide.

6. In a bolt machine, the combination of a bearing and means for revolving a bolt, a guide fixed to said bearing, a slide adapted to reciprocate along said guide to and from

said means, a tool holder fulcrumed on said slide, and means for setting said tool holder relatively to said slide.

7. In a bolt machine, the combination with means for revolving a bolt, of a fixed guide, a slide adapted to reciprocate along said guide, a tool holder fulcrumed on said slide, a cam fixed to said tool holder, means in the path of movement of said cam for determining its position and regulating the position of said holder, and means for holding said cam in contact with said means first named.

In testimony whereof we have hereunto set our hands this 26th day of June, 1913, in the presence of the subscribing witnesses.

ARTHUR M. HARRINGTON.
ROBERT F. SCOTT.
